(57) **CLAIM**

The ornamental design for a handle for a stick vacuum cleaner, as shown and described.

DESCRIPTION

FIG. 1 is a perspective view of a handle for a stick vacuum cleaner showing our new design;

FIG. 2 is a left side elevational view thereof;

FIG. 3 is a right side elevational view thereof;

FIG. 4 is a rear elevational view thereof;

FIG. 5 is a front elevational view thereof; and,

FIG. 6 is an enlarged top plan view thereof.

The components outlined in broken lines in the figures form no part of the claimed design.
